UNITED STATES PATENT OFFICE.

THOMAS E. STURTEVANT, OF DOVER, NEW JERSEY, ASSIGNOR TO McKIERNAN-TERRY DRILL COMPANY, OF DOVER, NEW JERSEY, A CORPORATION OF NEW JERSEY.

ROCK DRILL.

Application filed May 1, 1920. Serial No. 378,090.

To all whom it may concern:

Be it known that I, THOMAS E. STURTEVANT, a citizen of the United States of America, and a resident of Dover, Morris County, and State of New Jersey, have invented certain new and useful Improvements in Rock Drills, of which the following is a specification.

The present invention relates particularly to hammer drills and the objects of the invention are to simplify and to improve drills of this type, particularly as regards the front end and bit support construction.

The invention involves a number of novel features of construction, combinations and arrangements of parts as disclosed in the following specification.

In the drawing accompanying and forming a part of this specification I have illustrated one of the practical embodiments of the invention, but wish it understood that the structure may be modified without departure from the true spirit and scope of the invention as defined in the appended claims.

Figure 1 in the drawing referred to is a broken sectional view of the forward end and bit support structure of a drill having the invention incorporated therein, the section being taken on the line 1-1 of Fig. 3.

Figures 2, 3 and 4 are cross sectional views of the same as taken on substantially the planes of lines 2-2, 3-3 and 4-4 of Figure 1.

Fig. 5 is a sectional plan view of some of the parts shown in the other figures of the drawing, the section being taken on the line 5-5 of Fig. 3.

The numeral 5 in Figure 1 designates the piston guide between the front end of the cylinder and the bit support structure of a rock drilling engine and 6 the fluted forward end of the piston operating therein. This fluted portion of the piston operates in the usual way in the fluted rotating nut 7 which is screwed or otherwise secured in the end of the carrier sleeve 8. This sleeve is of novel construction in that its outer end is reduced as at 9 and provided with a bore 10 forming a guide for the drill bit 11 and this bore is notched at opposite sides, as indicated at 12 in Figure 2, to admit the wings or transverse lugs 13 of the drill.

The drill steel after being entered in the carrier sleeve is held against rotation therein

by means of the lock bushing 14, formed with drive shoulders 15 for engagement with the wings of the bit which is secured non-rotatably to the carrier sleeve by means of the longitudinal keys 16 welded in slots 17 formed in the sleeve and engaging loosely in key slots 18 cut in the periphery of the lock bushing 14.

These keys, as shown in Figure 3, are preferably disposed directly outside of the drive shoulders 15, said drive shoulders providing sufficient metal at these points for the cutting of the key slots 18 without weakening the strength of the lock bushing.

Also mounted in the carrier sleeve in back of the lock bushing are the usual guide 19 and spacer 20.

Another important feature of this invention is the making of the carrier sleeve 8 all in one piece and constructing it as a casing 75 to provide the strong, rigid, unitary support for the lock bushing 14, bit guide 19, the spacer 20 and the rotary nut 7. Accordingly, I have provided a cylindrical casing 21 in which the carrier sleeve is rotatably supported and which is formed at its forward end with an inwardly extending annular flange 22 overlying an annular shoulder 23 provided at the outer end of the carrier sleeve 8. Also the forward end of the carrier sleeve is shown as reduced and as having a bearing at 24 in the annular confining flange of the casing sleeve 21.

The casing sleeve 21 may be connected to the engine by the usual side bolts, such as 90 1 have indicated at 25 in Figure 2.

The construction disclosed is particularly simple and strong and consists of but few parts, which are readily assembled and disassembled as required. The carrier sleeve 95 when removed from the casing carries with it the lock bushing 14, the bearing bushing 19, the spacing sleeve 20 and the rotating nut 7, which assembly may be treated as a single unit as the nut holds these parts together tightly. These several parts are, however, readily removable from the carrier by unscrewing the rotating nut 7 which, when it is removed, permits the other parts to slide out of the carrier. A further advantage follows from the fact that the nut, the spacer, the bearing bushing, the lock bushing and the carrier are all separate parts, because these parts may then be made from different materials, each suited to a 110

particular purpose and designed to stand the wear and strains to which it is to be subjected. The construction also enables ready renewal of any of these parts in case they should become worn or broken.

What I claim is:

1. In a drill of the character described, the combination with a cylinder and a reciprocable piston therein, of a carrier sleeve having a reduced end provided with a guide bore for the shank of a drill bit, a lock bushing confined within said sleeve and keyed thereto, a casing rotatably receiving the carrier sleeve and secured to the cylinder, said casing having an integral annular flange engaging the reduced end of the carrier sleeve and rotatably confining the carrier sleeve therein, a nut in the end of the carrier sleeve opposite its reduced end, and means in the carrier sleeve between the nut and lock bushing arranged to cooperate with the nut to hold the lock bushing in position and to slidably but non-rotatively connect the carrier sleeve with the piston, combined with a drill bit having a shank fitting the bore in the reduced end of the carrier sleeve and laterally extending lugs adapted to pass through the notches.
2. In a drill of the character described, a casing, a carrier sleeve rotatably confined in said casing and provided with inwardly projecting keys, a lock bushing confined in said sleeve provided with grooves in its outer surface in line with said keys, said lock bushing having projecting drive shoulders on the inner wall thereof disposed substantially in line with the key grooves in its outer surface, a nut at the end of the carrier sleeve, and means in the carrier sleeve between the nut and the lock bushing arranged to cooperate with the nut to hold said lock bushing in position.
3. In a drill of the character described, the combination with a cylinder and a reciprocable piston therein, of a carrier sleeve having an open end and a reduced end provided with a guide bore for the shank of a drill bit and notches extending laterally from said bore, keys in said guide sleeve, a lock bushing insertable in the sleeve through

the open end thereof and engaging the reduced end portion of the sleeve, said lock bushing being provided with grooves in its outer surface in line with said keys and having projecting drive shoulders on its inner wall disposed substantially in line with the key grooves in its outer surface, for engaging lateral projections on the drill bit and a nut in the end of the carrier sleeve opposite its reduced end arranged to hold the lock bushing in position and to slidably but non-rotatively connect the carrier sleeve with the piston, combined with a drill bit having a shank fitting the bore in the reduced end of the carrier sleeve and laterally extending lugs adapted to pass through the notches.

4. In a drill of the character described, the combination with a cylinder and a reciprocable piston therein, of a carrier sleeve having an open end and a reduced end provided with a guide bore for the shank of a drill bit and notches extending laterally from said bore, keys in said guide sleeve, a lock bushing insertable in the sleeve through the open end thereof and engaging the reduced end portion of the sleeve, said lock bushing being provided with grooves in its outer surface in line with said keys and having projecting drive shoulders on its inner wall disposed substantially in line with the key grooves in its outer surface for engaging lateral projections on the drill bit and a nut in the end of the carrier sleeve opposite its reduced end arranged to hold the lock bushing in position and to slidably but non-rotatively connect the carrier sleeve with the piston, combined with a drill bit having a shank fitting the bore in the reduced end of the carrier sleeve and in the spacer and laterally extending lugs adapted to pass through the notches.

In witness whereof, I have hereunto set my hand this 29th day of April, 1920.

THOMAS E. STURTEVANT.
